UNITED STATES PATENT OFFICE.

SIDNEY HACKES, OF MOUNT VERNON, NEW YORK.

LETTER AND NUMERAL OUTLINER.

1,063,969.

Specification of Letters Patent. Patented June 10, 1913.

Application filed February 12, 1913. Serial No. 747,861.

To all whom it may concern:

Be it known that I, SIDNEY HACKES, a citizen of the United States, a resident of Mount Vernon, in the county of Westchester, State of New York, have invented certain new and useful Improvements in Letter and Numeral Outliners, of which the following is a specification.

The invention relates to drawing instruments or devices and its main object is to provide a letter and numeral outliner of very simple construction, which may be easily manipulated for conveniently and quickly forming letters of the alphabet and numerals.

A further object of the invention is to so construct the device that it may be readily and quickly manipulated by an unskilled person, the method of manipulation and the various positions of the rule or drawing device being almost obvious from its construction.

The advantage of providing a rule or drawing instrument of simple construction which will enable an unskilled person to quickly and properly form letters and numerals, is obvious. It was primarily devised for the use of storekeepers and clerks, to enable them to make letters for show-cards or signs.

The device may be made in various sizes and may be used by sign painters and letterers of varying ordinary skill, it being practically impossible to improperly shape the letters and numerals and practically impossible to fail to make them of the right sizes and proportions.

There are other important objects and advantages of the invention which will appear hereinafter.

In the drawings, Figure 1 is a perspective view of the outliner; Fig. 2 a face view of the device in a slightly different form from that shown in Fig. 1; Fig. 3 a diagram showing the three positions of the outliner in drawing the letter "B"; Fig. 4 shows the outliner used to form the basis or principal lines of the letter "H"; and Fig. 5 a diagram showing the positions of the outliner in forming the letter "S".

The outliner as a whole is substantially the combination of the letter "H" and the letter "P," the right-hand vertical arm 1 of the letter "H" forming the upright member of the letter "P" and the open spaces between the upright arms of the letter "H"

being closed by horizontal members 2 and 3. The left-hand arm 4 of the letter "H" is prolonged or extended below the horizontal member 3 to form the extension member 5 so that the left-hand edge of the arm 4 and of said extension provides a long ruling edge useful in forming such letters as "A," "V" and "W," as will be more fully hereinafter described. The arms of the letter "H" and the end members thereof are of the same width, as is also the extension member 5. The curved member forming the loop of the letter "P" is also of the same width as the members of the letter "H"; and the loop itself in its vertical dimension is equal to the upper half of the letter "H." This loop member is useful in forming the loops of the letter "B"; the upper loop of the letter "R" and is used in the formation of all curved lines of letters and numerals. The upright member or arm 1 forms the upright member of all loop letters.

The outliner is preferably formed of thin transparent material such as celluloid or the like when it is adapted for use in making small letters, that is to say, letters of an inch or two in height, but, of course, it may be made of any suitable thin material. To offset the outliner from the surface on which the marking is to be made I provide small studs 6. These studs may be formed integral with the outliner or they may be small pieces of rubber or the like attached thereto. By providing this means of offsetting the outliner the letters and numerals may be outlined by means of a drawing pen without any danger of blurring the ink marks. On the larger size devices, from twelve inches upward, the offsets will vary in height from one quarter of an inch to one inch. This will permit a skilled operator to directly use a paint brush to "cut" or "block out" letters without any preliminary marking and prevents smudging of the edge lines. In order that the letters shall be of uniform size the openings between the arms of the letter "H" are of the same size and the opening within the loop member is of the same height as the opening between the arms of the letter "H." Said openings being also of equal width in their greatest dimension horizontally. To facilitate the manipulation of the outliner the upper edge of the member 2 is provided with gage marks as shown and the middle of the arm 2 is indicated by the gage mark lettered A. For the purpose of indi-

cating the use and various positions of the 5 outliner the various members are lettered as shown *a*, *b*, *c*, *d*, *f*, *h* and *k*. Of course, it will be understood that any designating characters may be used which would be convenient in writing a description of the method of using the device.

In Fig. 2 is shown a slightly different form of the device, the loop member 7 being 10 extended downwardly from the arm 1 of the letter "H" and connected to the horizontal member 3. It is to be noted that this form of the device consists of the letter "H" with the openings between the ends of the arms 15 closed by horizontal members, and a loop member, said loop member being adapted to be used for forming loop letters and all curved lines. In this form of the device it is also to be noted that the extension member 5 20 may be dispensed with, the extension of the arm 1 giving a long straight edge and serving the same purpose as the said extension 5.

In Fig. 3 is shown a diagram illustrating one method of forming the letter "B." In 25 forming this letter it is first desirable to form the outlines of the letter "H", completing the left-hand edge of the left-hand arm. The position of the outliner for this purpose is shown by the dotted lines *a*. The 30 outliner is then moved to the left to the position shown by the dotted lines *b* to form the upper loop of the letter "B". It is then moved downwardly to the position shown by the dotted lines *c* to form the 35 lower loop. The letter "B" is shown in full lines in Fig. 3 and the various positions of the outliner are shown by the dotted lines of different character. Of course, the user 40 of the device may manipulate it in any way desired to secure the outlines of the various letters and the method just described is merely used for the purposes of illustration. The letter "B" may also be formed by first drawing the letter "P" and then dropping 45 the outliner down so as to use the loop portion for forming the lower loop of the letter "B". It is obvious that the letter "T" may be formed by various methods of using the outliner.

50 In Fig. 4 is shown the method of outlining the main lines of the letter "H". The inner edges of the upright members near the upper and lower ends thereof may be readily completed in any desired manner by shifting the outliner and using it as a rule.

In forming the letter "S" it is desirable 55 to first make the outlines of the letter "H" so that the letter "S" will be properly placed and to give the lateral and vertical dimensions of the loops. The outliner is 60 then placed in the various positions indicated by the dotted lines in Fig. 5. The dotted lines *d* indicate the position of the outliner when forming the letter "H" as 65 the basis for the final letter "S". After

forming this foundation or base the outliner is shifted to the position shown by dotted lines *e* which enables the operator to form the portion 8 of the final letter. The outliner is then shifted to the position shown 70 by dotted lines *f* which enables the operator to form the curved portion 9 of the final letter. The device is then shifted to the position shown by the dotted lines *g* which 75 enables the operator to form the portion 10 of the letter, the line *F* shown on Fig. 1, indicating the end of the portion 10 of the letter "S". To complete the letter the outliner is placed in the position indicated by the dotted lines *h*, this last position enabling 80 the operator to make the portion 11 and to thereby complete the letter. These few diagrams are merely given by way of illustrating the use of the device and it will be obvious to any one that the other letters 85 of the alphabet may be similarly made by properly manipulating the outliner.

In forming letters such as "A", "V" and "W" the long edge formed by the extension member 5 enables the operator to draw the 90 lines on the proper angle. Without this extension the upright member would be too short and the unskilled operator would be inconvenienced in drawing the said inclined lines accurately.

95 It is manifest from the foregoing that some of the letters of the alphabet can be practically completely outlined with the device in one position, such letters being "I", "H", "U", "J", "E", "L" and "P". 100 Other letters require the device to be shifted into two or more positions. It is obvious that this device assures uniformity of height and width of letters and exact duplication thereof, and the same is true as to 105 numerals. The device may be made in very large sizes for the use of sign painters in marking out letters on walls, fences and the like, thereby effecting a great saving of time and enabling comparatively unskilled 110 workmen to produce very satisfactory and uniform results.

Usually in sign writing and in lettering the painter first draws the upper and lower 115 guide lines for the letters. In the use of the device described herein it is found desirable to draw said guide lines as it materially facilitates the manipulation of the outliner.

What I claim is:

1. An alphabet outliner substantially in the form of the letter "H" with the spaces between the ends of the arms thereof closed by horizontal members and with a loop member connected thereto.
2. An alphabet outliner substantially in the form of the letter "H" with the spaces between the ends of the arms thereof closed by horizontal members and with a loop member connected thereto, said loop mem-

120

130

ber extending outwardly from the right-hand vertical arm of the "H" member.

3. An alphabet outliner substantially in the form of the letter "H" with the spaces between the ends of the arms thereof closed by horizontal members and with a loop member connected thereto, said loop member extending horizontally from the upper portion of the right-hand arm of the "H" member.

4. An alphabet outliner substantially in the form of the letter "H" with the spaces between the ends of the arms thereof closed by horizontal members and with a loop member connected thereto, all of the arms of said members being of uniform width.

5. An alphabet outliner substantially in the form of the letter "H" with the spaces between the ends of the arms thereof closed by horizontal members and with a loop member connected thereto, one of the vertical members of the "H" member being prolonged to form an extension member.

by horizontal members and with a loop member connected thereto, all of the arms of said members being of uniform width, the horizontal and vertical dimensions of the openings in the loop member and in the "H" member being equal.

25

6. An alphabet outliner substantially in the form of the letter "H" with the spaces between the ends of the arms thereof closed by horizontal members and with a loop member connected thereto, one of the vertical members of the "H" member being prolonged to form an extension member.

30

In testimony whereof I hereunto affix my signature in the presence of two witnesses.

SIDNEY HACKES.
